Primary Examiner — Clint A Samuel

(57) **CLAIM**

The ornamental design for LED candle as shown and described.

DESCRIPTION

The patent or application file contains at least one drawing executed in color. Copies of this patent or patent application publication with color drawing(s) will be provided by the Office upon request and payment of the necessary fee.

1. LED candle

1.1 is a front and top perspective view of an LED candle showing my new design;

1.2 is a bottom perspective view thereof;

1.3 is a top plan view thereof;

1.4 is a side plan view thereof;

1.5 is a front, top and elevation view thereof; and

1.6 is a bottom view thereof.

1 Claim, 6 Drawing Sheets
